(57) **CLAIM**

The ornamental design for a shaver, as shown and described.

DESCRIPTION

FIG. 1 is a first perspective view of a shaver showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of a portion of the shaver shown within the area designated as 9 in FIG. 1.

The broken lines shown in the drawings illustrate portions of the shaver that form no part of the claimed design. The dot-dash broken lines encircling portions of the shaver in FIG. 1 and illustrated enlarged view in FIG. 9 form no part of the claimed design.

1 Claim, 9 Drawing Sheets
